ABSTRACT

A process for disposing of high sulfur-containing residual oil is disclosed wherein a high sulfur vacuum residual oil is hydrocracked and hydrodesulfurized in an upflow, high pressure, high temperature, ebullated bed reactor, the effluent fractionated, and the 975°F. + fraction further subjected to separation by solvent extraction. The extract consists of gas oils, while the raffinate, containing most of the remaining sulfur, is partially oxidized to yield hydrogen which is recycled to the hydrocracking reactor. The heavy gas oil fraction from the extract may also be recycled to extinction in the hydrocracker.

PROCESS FOR REDUCTION OF HIGH SULFUR RESIDUE

CROSS REFERENCE TO RELATED APPLICATION

This application is a continuation-in-part of the co-pending and related application Ser. No. 230,910, filed Mar. 1, 1972 now abandoned.

BACKGROUND OF THE INVENTION

This invention relates to a process for refining hydrocarbon oils. More particularly it relates to a process for efficiently treating high sulfur, heavy hydrocarbon oils boiling above 975°F.

Many of the crude oils available as energy sources contain significant amounts of sulfur. Until recently, the sulfur inclusion did not present too significant a problem. This was because after initially treating the crude oil by normal distillation and fractionation, the sulfur was for the most part concentrated in the vacuum and atmospheric bottoms or residual oils. These residual oils contained significant amounts of heavy hydrocarbons boiling higher than 975°F. and were utilized by blending, until the present anti-pollution requirements restricted the use of high sulfur fuels. Various processes have been developed to refine the vacuum and atmospheric residual oils in order both to recover lighter oils and to desulfurize and otherwise upgrade the oil. One of these processes is termed the "H-Oil Process" and is exemplified by several issued patents, such as U.S. Pat. No. 3,207,688 issued Sept. 21, 1965 to Roger P. Van Driesen for a hydrocracking process. Briefly the H-Oil process is a high pressure (i.e., pressures of from 1,000 to 4,000 psi,) and high temperature (above 650°F.) catalytic hydrorefining treatment utilizing an upflow reactor, solid particulate catalyst, and large volumes of hydrogen to treat a hydrocarbon oil in the liquid phase.

Regardless of the efficacy of this treatment, after removal of the treated hydrocarbons and separation into desired streams, there remains a portion which contains the sulfur compounds not removed as hydrogen sulfide or other outgases. This portion constitutes the high sulfur residue of the hydrorefining treatment, sometimes characterized as asphalts, and at present, due to stringent environmental controls, disposal of this residue as a fuel is significantly limited and poses a problem to the refinery.

SUMMARY OF THE INVENTION

We have therefor invented a process for disposing of the high sulfur residues resulting from the high temperature, high pressure catalytic hydrorefining of sulfur-containing, heavy hydrocarbon oils, in which at least 95 vol.% boils above about 975°F., and obtaining essentially only low-sulfur hydrocarbon products boiling below 975°F. The process comprises:

- a. hydrocracking and hydrodesulfurizing said heavy hydrocarbon oil boiling above about 975°F. with hydrogen in a hydrogen refining zone, at a pressure from about 1,000 psi to about 4,000 psi and a temperature of between 650°F. and 950°F., by passing said oil and hydrogen upwardly through a particulate catalyst bed in said zone to obtain a hydrorefined oil,
- b. fractionating the hydrorefined oil, obtaining therefrom at least one residual fraction boiling above

about 975°F. and at least one fraction boiling below 975°F.,

- c. solvent deasphalting said fraction boiling above about 975°F. to give a deasphalted gas oil and a raffinate and,
- d. partially oxidizing said raffinate to extinction, to obtain a hydrogen stream therefrom, sufficient to meet the requirement of step (a) (or equivalent in quantity to the hydrogen used in step (a)).

BRIEF DESCRIPTION OF THE DRAWING

The FIGURE illustrates, in block diagram form, one version of the process according to the present invention. It is to be noted that the only products entering this system are the defined feedstocks and that the only products from the system, apart from H₂S by-product gas, are low-sulfur hydrocarbons boiling below 975°F.

DESCRIPTION OF THE PREFERRED EMBODIMENTS

Briefly, our process contemplates incorporating a solvent deasphalting step and a partial oxidation of the resultant raffinate with the step of the severe catalytic hydrorefining of a vacuum or atmospheric residual oil containing significant amounts of sulfur. This combination of steps furnishes a satisfactory answer to the problem of high sulfur hydrocarbon residues. The term hydrorefining includes processes such as hydrocracking, hydrodesulfurization, hydrodenitrogenation, hydrodemetalization, etc.

The terms "H-Oil Unit," Deasphalting Unit" and "Partial Oxidation Unit" are well-known and used in petroleum refining. A broad description of such terms can be found in "Hydrocarbon Processing", Sept., 1970 (Gulf Publishing Company, Houston, Tex.).

The following broadly describes the process diagrammatically illustrated by the FIGURE.

In the FIGURE, the hydrogen refining zone is provided by an H-Oil reactor. The H-Oil reactor is an upflow catalytic reactor containing a particulate hydrodesulfurization catalyst and maintained at a temperature of between 650°F. and 950°F., preferably between 750°F. and 900°F. Pressure can range from about 1,000 to about 4,000 psi, preferably between about 2,000 and 3,000 psi. Space velocity maintained in the reactor is sufficient to maintain the particulate catalyst in an expanded state. The quantity of hydrogen required may be between 1,000 and 50,000 cu.ft. of hydrogen per barrel of oil, but is preferably between about 5,000 and 10,000 SCFB. The parameters of the H-Oil process can be adjusted to furnish varying levels of cracking (or conversion) and desulfurization.

The feed for the H-Oil reactor is typically a heavy residuum from conventional atmospheric or vacuum fractionator bottoms. It is emphasized that the feed for the process of this invention is a heavy hydrocarbon feed which is characterized in that at least 95% of the feed boils above about 975°F. Broadly, the sulfur content of such feedstock ranges from about 1 to about 10 wt.%, preferably from about 2 to about 8 wt.%, and the metal content can range up to about 1,000 ppm. Broadly, this feed represents material which in the past had a low value and was typically blended off.

If desired, multiple H-Oil reactors can be employed, such as in a parallel arrangement. The effluents from the reactor and associated fractionators typically comprise (a) a 650°F. - fraction (light ends, middle distil-

lates etc.), (b) a 650-975°F. gas oil fraction, and (c) 975°F.+ heavy residual bottoms from vacuum fractionation. Fractions (a) and (b) typically go to additional processing units. Previously, the 975°F.+ bottoms were sent to blending. An important part of this invention is that all these 975°F.+ heavy bottoms are now processed in a deasphalting unit, and all the resultant deasphalting bottoms (raffinate) are partially oxidized to produce hydrogen for use in the H-Oil unit. This invention is characterized by its versatility in handling the defined feedstocks. If, for example, a high sulfur feed requires more hydrogen in the reactor, the conversion level in the reactor is adjusted (in this case, lowered) to furnish a larger amount of unconverted feed having the characteristics of asphalt. This asphalt fraction is deasphalting, furnishing more feed to the partial oxidation unit, which can thus furnish more hydrogen to the reactor. Conversely, a lower hydrogen requirement results in a higher conversion level in the reactor. This invention eliminates the heavy high-sulfur residue, in that there are not 975°F.+ residues remaining after completion of the process. This invention contrasts with prior art processes which result in the net production of some 975°F.+ residues. Essentially, the steps of the process are interdependent, in that one portion of this process depends on the other parts. Thus, a given feedstock uses a certain amount of hydrogen for a given degree of conversion, desulfurization etc. From this conversion, a certain amount of deasphalting bottoms is available and used as feed for the partial oxidation unit, which in turn furnishes the hydrogen sufficient and necessary, or equivalent in quantity, for processing of the feedstock. Thus, no 975°F.+ high sulfur residue is produced. In other words, the deasphalting and partial oxidation unit feed rates are adjusted to produce the precise hydrogen requirements needed in the H-Oil hydrocracking, hydrodesulfurization, etc. step. The deasphalting feed rate is adjusted by changing the 975°F.+ conversion in the H-Oil Unit. In essence, no 975°F.+ high sulfur heavy residue, or deasphalting bottoms, remains.

The deasphalting unit includes apparatus for deasphalting, fractionation, solvent recovery, etc. The heavy bottoms feed to this unit will typically have an API gravity between about -5° and about +10° and a sulfur content between about 1.5 and about 7.0 wt.%. The important effluents from this unit are (a) deasphalting gas oil and (b) deasphalting bottoms. The deasphalting gas oil stream will typically have the characteristics of from about +2° to about +15° API gravity and from about 0.5 to about 5.0 wt.% sulfur, while the deasphalting bottoms will have a gravity of from about -10° to about -2° API and from about 2.5 to about 8 wt.% sulfur. In one embodiment of this invention, the deasphalting gas oil stream is recycled to the H-Oil feed, as shown by the dotted line in the FIGURE. Previously, this stream was typically blended, but recycling now upgrades this stream by hydrocracking and hydrodesulfurization. If this system is recycled, the hydrogen requirement in the H-Oil reactor is greater than if this stream is sent to other processing units. Typical operating conditions for a solvent deasphalting unit are well known in the refining industry. The solvents used are typically C₃-C₈ paraffins, with the solvent:residuum vol. ratio ranging from about 2:1 to about 10:1. The temperature can range from about 125°-600°F., with the pressure ranging from about 200-1,000 psi.

An example of partial oxidation processes suitable for use in practicing the invention is the Synthesis Gas Generation Process of Texaco. This is a continuous, non-catalytic process for the production of hydrogen by partial oxidation of gas or liquid hydrocarbons. A carefully controlled mixture of preheated fuel, in this case the deasphalting bottoms (raffinate), and oxygen is fed to the top of a reactor. Free oxygen first reacts with fuel to produce CO₂, water vapor and heat. A secondary exothermic reaction between the gases and additional fuel forms hydrogen and CO. In the case of liquid fuel feed, steam is also injected to the reactor.

Effluent from the reactor is then charged to a shift converter with high-pressure steam, which is generated at no cost by utilizing the heat content of the generator-effluent gas in a direct-quenching system or a waste-heat boiler. In the shift converter, CO is converted to CO₂ with accompanying production of H₂.

The gaseous effluents from this unit are subjected to conventional clean-up steps, with hydrogen and H₂S being the desirable components. Typically, the effluent hydrogen stream has a purity of greater than 60 vol.%, suitable for use as the hydrogen source for the H-Oil unit.

The combination of the above steps offers a convenient method of utilizing high-sulfur high-boiling oils, such as from petroleum, coal or other sources. The defined feedstock is known and typical. Solvent deasphalting is a convenient and well-known method of extracting gas oil from residua. The partial oxidation step utilizes deasphalting bottoms as a source of feed, of hydrogen production and of recoverable sulfur. The hydrogen produced satisfies the requirement of the H-Oil reactor feed. The gas oil effluents can be further processed in other units. An upgrading of the high-sulfur feed of the H-Oil reactor takes place and no 975°F.+ residue results.

In practicing the invention, the operating conditions in the various units are adjusted so that the deasphalting bottoms are consumed in the partial oxidation unit, with the concurrent production of enough hydrogen to satisfy the needs of the H-Oil unit or additional units. Thus, the net products of the process are low-sulfur hydrocarbon streams boiling below 975°F.

With a view to further illustrating the process of this invention, the following example is given.

EXAMPLE

A residual oil feedstock comprising 44,000 BPSD of 4.8° API oil containing 4.6% sulfur and 250 ppm metals (vanadium and nickel), and having 100 vol.% boiling at 975°F., is subjected to severe catalytic hydrocracking, hydrodesulfurization, hydodemetalization, hydrodenitrogenation, etc. in an H-Oil reactor to yield the fractions shown below, totaling 46,464 BPSD of C₄+ liquid of 24.0° API containing 1.1% sulfur.

Feed Stock Inspection

Boiling Range 975°F.+, Vol. %	100
Gravity, Degrees API	4.8
Sulfur, Wt. %	4.6
Metals, Vanadium + Nickel, ppm	250

H-Oil Yields and Properties

C ₄ + Liquid ° API	24.0
Sulfur, Wt. %	1.1
Conversion of Feed, %	75

Fractionation of the effluent of the H-Oil reactor gives these results:

Fraction	Volume %	Sulfur, Wt. %	BPSD
C ₄	2.4	0.01	1056
C ₅ - 400°F.	19.2	0.1	8448
400 - 650°F.	30.8	0.5	13552
650 - 975°F.	28.2	1.0	12408
975°F.+	25.0	2.6	11000
	105.6	1.1	46464

Chemical hydrogen consumption (SCF/bbl) = 1280

The vacuum bottoms from the H-Oil system, comprising 11,000 BPSD of 975°F.+ material containing 15 2.6% sulfur, are subjected to deasphalting to extract 7,200 BPSD of 6.4° API deasphalter gas oil having a 2.1 % sulfur content. The deasphaltered bottoms, i.e., the raffinate, comprising 3,800 BPSD of -7.0° API material having a 3.5% sulfur content, are introduced as 20 feedstock to the partial oxidation unit for generation of hydrogen, which is recycled as make-up hydrogen to the H-Oil reactor system.

The above example illustrates high (75 vol.%) conversion of the feedstock to lower boiling products. Hydrogen requirements for other feedstock types boiling above 975°F.+ may vary, thus necessitating different H-Oil conversion levels (or degree of hydrocracking). The feedrates to the downstream units, i.e., processing steps downstream of the H-Oil unit, will thus be adjusted to produce the desired hydrogen and eliminate any production of 975°F.+ high sulfur residue or deasphaltered bottoms in excess of that required.

Having fully described our invention and wishing to cover those modifications and variations which would 35

be apparent to those skilled in the art without departing from either the scope or spirit thereof.

We claim:

1. A process for treating a sulfur-containing heavy hydrocarbon oil, with at least 95 vol.% boiling above about 975°F., to obtain essentially only low-sulfur hydrocarbon products boiling below 975°F., said process comprising, in combination:

a. hydrocracking and hydrodesulfurizing said heavy hydrocarbon oil with hydrogen in a hydrogen refining zone, at a pressure from about 1,000 psi to about 4,000 psi and a temperature of between 650°F. and 950°F. by passing said oil and hydrogen upwardly through a particulate catalyst bed in said zone, thus maintaining the catalyst bed in an expanded state to obtain a hydrorefined oil;

b. fractionating the hydrorefined oil, obtaining therefrom at least one fraction boiling above about 975°F. and at least one fraction boiling below 975°F.;

c. solvent deasphalting said fraction boiling above about 975°F. to give a deasphaltered gas oil and a raffinate;

d. partially oxidizing said raffinate to extinction, to obtain a hydrogen stream therefrom equivalent in quantity to that used in step (a), and

e. recycling the hydrogen from step (d) to step (a).

2. The process of claim 1 in which step (a) is conducted at a temperature range of about 750°-900°F. and a pressure range of about 2,000-3,000 psi.

3. The process of claim 1 wherein the deasphaltered gas oil from step (c) is recycled, to extinction, to step (a).
